FIG. 1.

Inventor.

Robert E. Hinckley
Mary Walker.

FIG. 2.

Robert E. Hinckley.

UNITED STATES PATENT OFFICE.

ROBERT EMMETT HINCHEY, OF AURORA, MISSOURI.

ADVERTISING MACHINE.

Application filed September 29, 1920. Serial No. 413,505.

To all whom it may concern:

Be it known that I, ROBERT EMMETT HINCHEY, a citizen of the United States, residing at Aurora, in the county of Lawrence 5 and State of Missouri, have invented new and useful Improvements in a One-Story Moving Display Advertising Machine, of which the following is a specification and is illustrated in the accompanying drawings.

My invention relates to a one-story, two-section moving-display advertising machine, with means to successively display cards bearing advertisements, photographs, illustrations, designs, etc. The operative mechanism comprises a combination of one set of machinery secured to the bottom of a horizontal rectangular-shaped supporting-frame, a series of vertical card-display carrying-frames arranged in sets, one set to each section. Said sets of frames rest upon two like transverse slides or run-ways and are bodily movable transversely, in opposite directions, the diagonally opposing endmost-frames being delivered into the horizontal portions of an endless-track, where they are individually and consecutively transferred from one set to another and vice versa. It is notable that many features of my machine are similar to the advertising device disclosed in my 20 copending application S. N. 413,504, filed Sept. 29, 1920, which is a two-story device, having both horizontal and vertical movements.

The machine is for both or either interior 35 or exterior displays of any size from 2 x 3 inches to 20 x 30 feet or larger, according to requirements, and may have any number of display-carrying frames from three up.

Fig. 1 is a flat view of the lower part of 40 the machine as seen by looking down upon it.

Fig. 2, a perspective of the front elevation of the apparatus shown in Fig. 1.

I attain the foregoing features by the mechanism illustrated in the accompanying 45 drawings, in which—

Similar numerals and characters refer to similar parts throughout said drawings.

Referring to the drawings, F represents a supporting-frame, which may be made of 50 metal or any suitable material, divided into two parallel sections, C first section and D second section which are separated by a narrow vertically disposed space L. A represents a set or series of frames supported 55 by the first section C, and B another set or

series of like frames supported by the second section D. These frames may be of the same material as the supporting-frame F, each made with a groove in the inner part and preferably open at the top to receive cards 60 bearing advertisements that may be slipped in back-to-back, in order that the displays may be presented to view on both sides of the machine. The construction of the supporting-frame F is such that the sections C 65 and D, each have a front and rear display-opening, making in all four openings, opposite which four different advertisements may be viewed at all times, each display being exposed to view twice on its side of the 70 machine.

The card-supporting frames of the sets A and B are movable in what we may term an endless-pathway, the first section C and the second section D constitutes the two trans- 75 verse sections or portions of said endless-pathway, and will, therefore, be designated hereinafter interchangeably with said sections as C and D, in which one set of frames A are movable, forwardly and bodily, in the 80 first transverse section or portion C, and the other set of frames B are movable in an opposite direction, rearwardly and bodily, in the second transverse section or portion D.

In each instance after the above mentioned 85 bodily movements, the diagonally opposing endmost frames 5 are adapted to be transferred singly and consecutively from one set, as A through the front horizontal portion E, to the other as B, and vice versa, 90 through the rear horizontal card-displaying portion E', by means of notches 4 cut in the center of the under edge of the frames 5, co-operating directly with a stiff-pin 3 that is mounted on an endless-chain carrying-de- 95 vice 1, located in the bottom of the apparatus, under said sets of frames A and B.

Said endless-chain is operated by a large sprocket-wheel 2, fastened to a gear-shaft O that is continuously rotated by the driving- 100 gear N, (any suitable gear may be used,) which, in turn, is engaged by the operative-power, preferably an electric-motor M, (see Fig. 2.) Fig. 1 shows the endless-chain 1 passed about the aforementioned sprocket-wheel 2, and one small sprocket-wheel 22, mounted on shafts O and O', supported under section D, and about sprocket-wheels 23 and 24, mounted on shafts O² and O³, sup- 105 ported under section C. Said sprocket- 110

wheels, so positioned, are adapted to balance and guide said endless-chain 1 in a horizontal rectangular position, in order that a single stiff-pin 3 mounted thereon, may have 5 co-operation with the several parts of the operative mechanism that are located in its path at suitable intervals, to effect intermittent movement, bodily and singly, of all the frames 5 through said endless-pathway, composed of the transverse portions C and D, and the horizontal card-displaying portions E and E'. As may be seen by Fig. 1, said endless-chain 1 is supposed to be continuously in motion, so the above mentioned intermittent movements are governed by the time it takes pin 3 to travel from one cooperative part to the next, engaging and releasing them in turn, as will hereinafter be more fully described.

20 By reference to Fig. 1, the dotted lines represent the positions of the card-receiving frames 5, arranged in sets A and B, showing the even line-up of the notches 4, that are cut in the center of the under edge of each 25 frame, serving in the transverse sections C and D, as a passage for the actuating pin 3. When in the horizontal card-displaying portions E and E', said notches 4 become cooperative with said pin 3, to effect individual movements of the frames 5 from one set, A, to the other, B, and vice versa. Pin 3 having arrived at the points where it turns about sprocket-wheels 2 and 23, respectively, it leaves notches 4 in frames 5. To obviate 30 the possibility of the movements not being sufficient to place the frames exactly in their proper positions relative to the other frames 5 in the sets A and B, oscillatory hooked-bars 18 and 21, are provided to catch in said 35 notches 4 of the endmost frames 5, operating to pull them in into line, ready to be delivered into the transverse portions D and C. Said deliveries being made by the pressure of succeeding frames 5, in the passing, 40 against spring-lugs H—H' on front elbow-levers 10—10', and spring-lugs I—I' on rear elbow-levers 8—8', (the upper levers 8' with 45 spring-lug I' not shown in drawing, but supposed.)

50 When in the transverse sections or portions C and D of the endless-pathway, the card-supporting frames 5, are bodily movable, by means of said spring-lugs functioning simultaneously with opposing stiff-lugs, 55 all of which are provided on the outmost arms of two like sets of similar opposing, operatively connected, pairs of corresponding upper and lower elbow-levers, that are pivoted inside of the top and bottom of the 60 supporting-frame F.

Of these pairs of elbow-levers with their operative lugs, the two lower ones constituting two half sets are shown in Fig. 1. In the front part of the machine, lever 10 bearing a spring lug H, represents a central le-

ver, which is linked by a horizontal rod 16, to an opposite outmost elbow-lever 10 having a stiff-lug K. Said rod 16 also has operative connection with an elbow-lever 9, located in section C, that is actuated by pin 3 on the endless-carrier 1. In the rear of machine, Fig. 1, lever 8 bearing a spring-lug I, represents an opposite central elbow-lever, which is linked by a horizontal rod 15 to a similar outmost elbow-lever 8 having a 75 stiff-lug J. Said rod 15 functions the same as rod 16, except that it operates in an opposite direction, connecting with an elbow-lever 7 in section C, that is actuated by said pin 3. 80

Of the upper corresponding pairs of elbow-levers, only the outmost arms of the front said levers are shown, (see Fig. 2,) 10' bearing spring-lug H', represents the central upper elbow-lever linked by a horizontal rod 16' (not shown in drawing,) to an outmost elbow-lever 10' with its stiff-lug K'. 85

In the rear of the apparatus, Fig. 2, the upper corresponding elbow-levers, not shown in the drawing, but may be designated herein, by corresponding numerals and characters as 8' bearing spring-lug I', linked by a corresponding horizontal rod 15' to an outmost elbow-lever 8' with its stiff-lug J'. 90

These upper and lower pairs of levers are 95 forced into two like sets, by shafts 11 and 12 which extend vertically through space L, thereby connecting the two opposing central levers 8—8' and 10—10'. The rocking of the central lower levers 8 and 10 by rods 15 100 and 16, respectively, cause the pairs to function simultaneously, and the sets to work alike, but in opposite directions.

The sets of elbow-levers 10—10, 10'—10'; 8—8, 8'—8', are placed diagonally in opposite site positions, and are adapted by means of said lugs H—K, H'—K'; I—J, I'—J', to operate on all four corners of each co-operative endmost frame 5, thereby moving all of the frames 5, one against the other, transversely in opposite directions, the distance of the thickness of one frame 5. 110

The bodily movement of said frames 5, rearwardly, in the second section D, may be effected by said spring-lugs H'—H, that are 115 pivoted on the outmost arms of elbow-levers 10'—10, to engage the projections G, on the upper and lower inmost corners of the front endmost frame 5, assisted by stiff-lugs K'—K that are integral with the outmost 120 arms of elbow-levers 10'—10, adapted to hook over the top and under the bottom, near the outmost corners of said endmost frame 5.

The bodily movement of said card-receiving frames 5, forwardly, in the first section C, may be accomplished by similar spring-lugs I'—I that engage similar projections G, upper and lower, on the inmost corners of the diagonally rear endmost frame 5, as- 125 130

sisted by similar stiff-lugs J'-J that hook over the top and under the bottom, near the outmost corners of said frame 5.

The central levers have the spring-lugs 5 H-H' I-I' pivoted to their outmost arms to permit them to spring back behind the projections G on the opposing endmost frames 5, while the opposite arms have loops or slots P, to allow them to slip back 10 on rods 15 and 16, without moving said rods and other parts of the mechanism when said levers 10-10', 8-8' by the pressure of the passing frames 5, are being pushed in.

Said rods 15 and 16 have nuts on them 15 that catch and pull said levers 10-10', 8-8' when the frames 5 are to be moved bodily in the sections C and D, turn-buckles R to regulate their length and restraining-springs Q on their ends where they join 20 their respective actuating levers 7 and 9, to obviate the possibility of breakage or stopping of the machine. The rods and levers are returned to their normal positions by small springs S.

25 A link-chain 1 moved by a sprocket-wheel 2 has in it a stiff-pin 3 that extends up far enough to catch in notches 4 in frames 5, also to engage the ends of certain levers hereinafter described as it comes to 30 them. Pin 3 catches in notch 4 of the endmost frame 5 of the first section C, transfers it to the vacant space 25 in the second section D, leaving a space in first section C. By curving around sprocket-wheel 2, pin 35 3 leaves notch 4 releasing frame 5, passes on through notches 4 in several other frames 5 to engage elbow-lever 6 that moves straight-lever 17 which in turn oscillates hooked-bar 18, operating to catch in notch 40 4 of said released frame 5, thereby completing the horizontal movement in placing said frame 5 in the proper line to be delivered into the transverse section or portion D. Said delivery being made by a succeeding 45 frame 5, in the passing, pressing spring-lugs H-H' against the projections G of said preceding frames 5, lever 7 that pulls rod 15 rocking elbow-levers 8 8' thereby turning shaft 11 that runs up in the space L 50 between the two sections C and D, operating simultaneously two corresponding elbow-levers 8' 8' that are above the movable-frames 5 in the first section C. All four elbow-levers 8 8', 8' 8' with their curved lugs, 55 L-J, I' J' operate to move all frames 5 in first section C, forwardly, to fill up the space in the front part of said section C, and to leave a space in the rear of said first section C. Pin 3 passes around small 60 sprocket-wheel 22, preparatory to catching in notch 4 in the endmost frame 5 in the rear of the second section D, operating to transfer said frame 5 to the space in the rear of first section C, leaving another display in 65 view in the rear of second section D.

Pin 3 curves around sprocket-wheel 23, releasing said frame 5, moving on to engage elbow-lever 19 that operates lever 20 which in turn oscillates hooked-bar 21, operating to catch in notch 4 of said released 70 frame 5, thereby finishing the horizontal movement that might not have been quite completed by pin 3, in placing said frame 5 in line to be delivered into the transverse section or portion C, in the rear of section 75 C. The delivery of said frame 5 from the rear horizontal portion E' into the transverse portion C, is accomplished by a succeeding frame 5, in the passing, pressing spring-lugs I-I' against the projections G 80 of said preceding frame 5. Pin 3 passes on through several notches 4 in frames 5, to engage elbow-lever 9 that pulls rod 16, rocking upper and lower elbow-levers 10' 10', 10 10 simultaneously by means of connecting shaft 12, operating to move all frames 5 in the second section D, rearwardly, filling up the space in the rear and leaving a space 25 in the front of said second section D. Pin 3 moves on to engage notch 4 in 90 the front endmost frame 5 of the first section C, transferring said frame 5 to the space 25 in the front of second section D. These movements are repeated as long as the machine is kept running. 95

I am aware that prior to my invention moving-advertising machines have been made with display-carrying-frames, and with various movements in conjunction with endless-link-chains. 100

I, therefore, do not claim to be the original inventor of such mechanisms and movements in their entirety; but what I claim as new and different, and desire to cover and secure by Letters Patent is: 105

1. The combination in a one-story, two-section moving-display advertising machine, of a frame-work supporting an endless-pathway, consisting of a front and rear horizontal card-displaying portion, and two 110 oppositely disposed sections, constituting in themselves, two transverse portions with a narrow space therebetween, a series of card-display carrying-frames supported in said transverse sections to form first and second 115 sets, an endless-chain passed about a large sprocket-wheel mounted on a gear-shaft having a gear, and three small guide-wheels spaced apart in determinate positions, means to continuously rotate the shaft, a gear having operative connection between said shaft and the driving power, a single stiff-pin mounted on said endless-chain, adapted to the several tasks of transferring the frames from one set to the other and vice versa, of 120 actuating the means to move said frames in the transverse sections or portions, thereby placing them in position to be transferred, co-operative notches cut in the under edge of 125 the frames for operative engagement while 130

in the horizontal portions, elbow-levers oppositely positioned having arms disposed in timing distances in the transverse path of said actuating-means to effect intermittent 5 bodily movement of all the frames in the transverse portions, while said shaft is turning, substantially as described.

2. The combination, in a one-story moving-display advertising machine, comprising 10 a supporting-frame having sections spaced apart in horizontal alinement with a space therebetween, and shafts disposed vertically in the space, a plurality of vertical card-display carrying-frames arranged in sets, 15 an endless-chain having a stiff-pin mounted thereon, adapted to actuate the means to effect intermittent bodily movement of all the frames in said sets in opposite directions, comprising oppositely positioned sets 20 of elbow-levers composed of oppositely disposed, operatively linked pairs of upper and lower elbow-levers having lugs on the outmost arms to co-operate with the frames in the transverse sections, means to cause said 25 sets of levers to function alike, and the pairs of levers to operate simultaneously, shafts to

connect the central upper and lower elbow-levers, the inmost arms of said lower levers having operative connection with said actuating means, substantially as described. 30

3. The combination, in a one-story moving-display advertising machine, having sections spaced apart in horizontal alinement with a space therebetween, a framework supporting said sections, and provided with 35 four display-openings, two in each section oppositely disposed, and facing the horizontal portions of the endless-path, a series of card-receiving frames having notches cut in the center of the under edge, an endless 40 chain passed about a plurality of sprocket-wheels and operated by one of the sprockets secured to a continuously-rotated shaft of the drive-gear, a stiff-pin mounted on said chain, adapted to engage the notches in 45 said frames when in the horizontal portions to transfer the frames, singly and intermittently, from one set to the other and to deliver them into the transverse portions, substantially as described.

Sept. 27, 1920.

ROBERT EMMETT HINCHEY.
